UNITED STATES PATENT OFFICE.

CHARLES E. ADAMSON, OF BUFFALO, NEW YORK, ASSIGNOR TO ADDRESSOGRAPH COMPANY, OF CHICAGO, ILLINOIS, A CORPORATION OF ILLINOIS.

TYPE-RACK.

1,250,121.

Specification of Letters Patent. Patented Dec. 18, 1917.

Application filed October 20, 1915. Serial No. 56,936.

To all whom it may concern:

Be it known that I, CHARLES E. ADAMSON, a citizen of the United States, residing at Buffalo, in the county of Erie and State 5 of New York, have invented certain new and useful Improvements in Type-Racks, of which the following is a specification.

My improvement relates to type-racks and more particularly to racks which will enable 10 type to be readily distributed into their proper receiving spaces and as readily removed therefrom for setting up a type form, the rack being particularly designed for holding short type such as are used in du- 15 plicating or imitation typewriter-printing machines.

The principal object of my invention is the provision of a rack of this type in which type bearing different characters are re- 20 tained in convenient form so that a type of any character may be easily removed for setting the same into a type form and as readily inserted into its proper receiving space when distributing the type from a 25 form.

Another object of my invention is the provision of a type rack in which the type are arranged in a series of rows, a single row being provided for each character.

Another object is to provide a type 30 rack with obliquely-disposed type-receiving spaces leaning from the vertical not more than will give assurance that the type will gravitate in said spaces; and to provide 35 means for retarding the gravitating movement of the type as they approach the lower extremities of the type-receiving spaces and for retaining the lower end type of each row in its space so that all the remaining 40 type of the row will be checked in their gravitating movement by said lower end type.

A further object is to provide a type rack 45 for nicked type wherein suitable guides are provided to enter the nicks of the type and to provide said guides with type retaining means permitting the lower end type of each row to be readily disengaged from said retaining means.

A still further object is to provide a type 50 rack with obliquely-disposed type-receiving spaces separated by type-guiding bars and providing said bars at their lower extremities with an abutment, said bars having lateral flanges serving as guides which are 55 adapted for use in connection with type having guide nicks at opposite sides slightly wider than the thickness of the guides which enter said nicks.

A still further object of my invention is 60 the provision of a type rack with type-receiving spaces, from one end of which the type are to be removed as needed when setting up a form; and to so arrange said spaces in series that the lower ends of the 65 several series terminate in different horizontal planes.

With these and other objects in view, my invention consists in the novel features of 70 construction, and in the combination and arrangement of parts to be hereinafter described and more particularly pointed out in the subjoined claim.

In the drawings,—

Figure 1 is a front elevation of the type 75 rack.

Fig. 2 is a side elevation of the same.

Fig. 3 is an enlarged vertical section taken on line 3—3, Fig. 1.

Fig. 4 is an enlarged transverse section 80 taken on line 4—4, Fig. 3.

Fig. 5 is an enlarged vertical section taken on line 5—5, Fig. 4.

Fig. 6 is a detached perspective view of 85 one of the nicked type adapted to be retained in the type rack.

Referring now to the drawings in detail, like numerals of reference refer to like parts in the several figures.

The reference numeral 6 designates the 90 body portion of the type rack which comprises two side members 7 connected together by cross bars 8. These cross bars are secured to said side members by means of screws 9 which pass through said side 95 members and take into the ends of said cross bars, as best shown in Fig. 4. The body portion is supported in inclined position by

means of legs 10 pivotally secured at their upper ends to the side members 7, as at 11, and these legs are held in adjusted position by means of notched brace-bars 12 pivotally connected to said side members in a plane in advance of the pivots of said legs, said brace-bars extending rearwardly from their pivotal points of connection and having notches 13 at their lower edges into any of which stop pins 14 are adapted to enter, each of said pins extending outwardly from a guide 15 secured to the inner face of each supporting leg. The brace-bars pass between the guides 15 and the supporting legs and by adjusting the same with reference to the pins 14 the legs may be swung on their pivots and retained in any adjusted position with a view of increasing or diminishing the inclination of the body portion. At the lower end of the side members and also at the lower ends of the supporting legs, rollers 16, 17, respectively, are arranged so that the rack may be easily moved about.

Secured to the cross bars 8, which are arranged in sets, are obliquely-disposed type-guiding bars 18, each bar having opposite lateral flanges 19. These type-guiding bars are arranged in series, one series being above the other and the lower end of each bar is curved, as at 20, the curve being extended so that it terminates in an upward direction. The upper or outer face of each bar is provided with an abutment 21 formed by reducing the depth of the bar near its lower extremity. The various bars of each series are arranged side by side and spaced apart for the insertion therebetween of type 22, and for this reason the spaces between said bars may be termed type-receiving spaces. The flanges 19 of adjoining bars are arranged in opposition, and as the type are nicked at opposite sides, as at 23, the opposing flanges of the type-guiding bars enter the nicks 23 of the type and permit the latter to gravitate within the type-receiving spaces. Attention is invited to the fact that the nicks of the type are somewhat wider than the flanges 19 of the type-guiding bars are thick, so that the type have freedom in action and will easily gravitate in the type-receiving spaces while guided in their downward movement by said flanges.

The first type introduced into a type-receiving space gravitates to the lower extremity of said space, and as it rides over the curved portion 20 is retarded in its movement, due to the fact that it no longer travels by force of gravity after it reaches the center of said curved portion and depends more on momentum carrying the same forward in the space. The type therefore is carried to the forward extremity of the space with retarding speed and engages the abutment 21. All additional type inserted

in the same type-receiving space travel downward until they come in contact with the type already entered within said space. In this manner the type are held against accidental removal from the type-receiving spaces. Each of the spaces receives type of the same character and these spaces may be designated in any suitable manner so that the desired type may be quickly withdrawn, or type of certain characters entered in their proper spaces, said designations being preferably made on the upper and lower cross bars 8.

It is to be noted that at the extremities of the type-guiding bars they are beveled or cut away, as at 24, 25. This facilitates the entrance of the type into the type-receiving spaces and also the removal therefrom, and as the nicks of the type are wider than the flanges 19 of the type-guiding bars are thick, sufficient play will be provided underneath the flanges, and in removing the type it is therefore simply necessary to press the lower end type upwardly and thus free the same from the abutment 21 of the type-guiding bars, thence draw outwardly to remove the type from the rack. This will cause the remaining type in the space to slide on the type-guiding bars and bring the next type in engagement with the abutment 21 which in turn holds all the other type of said space against movement.

It is also to be noted that the three series of type-guiding bars have their curved ends terminating in the same vertical plane, one series above the other, thus making it convenient to remove the type from the rack.

The type to be set into a form are usually placed in line tubes, which may be constructed and positioned so that the type may be inserted into the tube directly from the type-receiving spaces in which they are held, and these tubes may be set into a chase to constitute the form from which the printing impression is to be made. When the type are to be distributed from a form, the line tubes are removed from the form and each placed so that the type can be discharged therefrom directly into the type-receiving spaces of the rack and be stopped in their descending movement by the highest type of the series in the spaces, and if it is the only type it will engage the abutment 21 of the type-guiding bars forming the space.

It will be apparent from the foregoing that changes in details of construction and variations in arrangement of parts may be resorted to without departing from my invention or sacrificing any of the advantages thereof.

Having thus described my invention, what I claim is,—

A type holding rack comprising a series of type-guiding bars having oppositely dis-

posed lateral flanges spaced apart to provide type receiving channels, means for obliquely supporting said series of type guiding-bars, the lower ends of said type guiding bars being curved outwardly and upwardly, and having abutments on the upper faces of said flanges adjacent their extremities

against which the lowermost type in each channel rests, said abutments being spaced apart to permit the type upon being lifted 10 slightly to be withdrawn longitudinally from said channels.

In testimony whereof I affix my signature.
CHARLES E. ADAMSON.
